UNITED STATES PATENT OFFICE.

JOHN R. CARTER, OF AUGUSTA, KENTUCKY, AND JOSEPH E. HAUSFELD, OF CINCINNATI, OHIO, ASSIGNORS TO ERNST H. HUENEFELD, OF CINCINNATI, OHIO.

DESIGN FOR AN ASH-PAN FRONT.

SPECIFICATION forming part of Design No. 33,798, dated December 25, 1900.

Application filed December 3, 1900. Serial No. 38,564. Term of patent 14 years.

To all whom it may concern:

Be it known that we, JOHN R. CARTER, residing at Augusta, in the county of Bracken and State of Kentucky, and JOSEPH E. HAUSFELD, residing at Cincinnati, in the county of Hamilton and State of Ohio, citizens of the United States, have invented and produced a new and original Design for an Ash-Pan Front, of which the following is a specification, reference being had to the accompanying drawings, forming part thereof.

In the accompanying drawings, Figure 1 is a perspective view, and Fig. 2 is a view in section of the same.

The leading feature of our design for an ash-pan front consists of a plate having an elongated opening and the portion of the plate on one side of the opening bulged outward.

1 represents the plate, having a top curved edge 2 and the sides and top of said plate curved slightly rearward. The plate 1 has an elongated opening 3, about midway between its top and bottom, and the plate above the opening is bulged outward over said opening, as shown at 4.

25

What we claim is—

The design for an ash-pan front shown and described.

In testimony whereof we have signed our names to this specification in the presence of 30 two subscribing witnesses.

JOHN R. CARTER.

JOSEPH E. HAUSFELD.
